UNITED STATES PATENT OFFICE

2,438,294

POSITION INDICATOR FOR CYLINDER
DOORS

Albert Matthews, Cincinnati, Ohio, assignor to
The American Laundry Machinery Company,
Norwood, Ohio, a corporation of Ohio

Application December 16, 1944, Serial No. 568,449

4 Claims. (Cl. 116—124)

1

This invention relates to work treating machines of that type in which the work is enclosed in a foraminous cylinder or drum which is rotatable within an outer stationary casing or tub for the purpose of subjecting it to the effect of treating fluid, typified, for example, by a wet washing machine using water and a soluble detergent, or a dry cleaning washer using a volatile solvent liquid, or even a drying tumbler in which cleaned work is dried by passing over it a stream of drying air.

In such machines both tub and cylinder are provided with doors which must be brought into registering relation in order to open both for the removal or insertion of work, and the drum driving and reversing mechanism usually includes a so-called "inch" device, manipulation of which makes it possible to rotate the drum in one direction or the other, or both, to bring the drum door into registering relation with that in the tub.

The present invention has for its object to provide simple and improved means for visually indicating to the operator when registering relation has been accomplished, so that it is unnecessary for him to open the tub door to determine the actual position of its door, thereby safeguarding him from any danger of accident and simplifying the task.

Still another object is to provide indicating means of the character described of such form as to enable it readily to be applied either to new machines when first built or to old machines already in use in the field.

Further objects of the invention in part are obvious and in part will appear more in detail hereinafter.

In the drawings, which represent one suitable embodiment of the invention,

Fig. 1 is a front elevation;

Fig. 2 is an end elevation; on a larger scale, from the right in Fig. 1; and

Fig. 3 is a detail front elevation on a larger scale, showing the indicator and scale.

The invention may be applied to any treating machine, of drum type, which includes doors on both tub and drum which must be brought into registration by drum rotation. For convenience and in no sense of limitation it has been shown in the drawings as applied to a washing machine for use in the laundry or dry cleaning plant.

The machine shown includes an outer tub or casing 10 provided with one or more doors 11 and within which is mounted a work holding cylinder or drum 12 also provided with doors 13 and

16 with end gudgeons 14 which rotate in suitable bearings in the tub end walls as is usual. The doors 11, 13 may be either hinged or sliding, but are shown as of the latter form. When they are in registering relation, or directly opposite each other, both doors may be opened (one in the cylinder and one in the tub or casing) to enable the work to be inserted or removed. To bring them into this relation requires special operating control of the drum driving mechanism, for which purpose it usually includes an inching device operable by any suitable controller, such as handle 15, to cause rotation of the drum in one direction or the other by corresponding movement of said handle. Since the drum driving and controlling mechanism including such inching device, forms no part of the present invention, it requires no description and has not been illustrated except for the incidental showing of handle 15, referred to.

To the projecting end of one of the cylinder gudgeons, or to a part secured thereto, I firmly secure, as by bolt 16, an arm 17 provided with a crank pin or shaft 18, the outer end of which passes through the eye of a clevis 19 held between two collars 20 on the crank pin. Said clevis is fastened, by lock nuts 21, to the threaded lower end of a long rod 22 which passes through a swivel eye 23 mounted in a bracket 24 supported on the casing. The upper end of rod 22 is bent laterally and forwardly to form an indicating pointer 22a, which works up and down in a vertical slot 25 in a housing 26 at one side of which is an indicating mark 27. This mark may be inscribed upon a small plate 28 fastened to the housing by a bolt 29 passing through a vertical slot 30 of the plate, enabling the plate to be adjusted vertically when installing and setting the mechanism, although this is not essential.

40 The operation is as follows:

When the mechanism is initially installed on a machine, either a new machine during the course of its construction in the factory, or an old machine already in use in the field, the tub door 11 is opened to expose the drum or cylinder to view and the inching handle 15 is moved in one direction or the other to rotate the drum, slowly, forwardly or rearwardly, until its door 13 is in exact registration with the door opening in the tub or casing. Then the arm or lever 17 is firmly secured to the cylinder gudgeon 14 in such position, circumferentially of the cylinder axis, that the projecting pointer 22a at the upper end of rod 22 projects outwardly through the slot 25. This pointer usually is fashioned in such

manner as to make it stand out and be quickly visible against the surrounding background, as by painting it white to contrast with the darker color of the housing. Next by loosening the lock nuts 21 and slipping the clevis off from the crank, the rod and clevis are relatively adjusted along their connecting threads to so adjust the effective over-all length of the rod as to make the pointer occupy a position at about the middle of the slot 25, and the clevis is thereupon restored to position on the crank pin and its collars 20 secured in place. Next, the indicating mark 27 is inscribed on the casing opposite to the pointer or, if said mark is on an adjustable plate 28, the latter is adjusted vertically to bring the mark opposite to the pointer.

With the parts so installed and adjusted or set, as the cylinder rotates, the crank arm 17 turns around the central axis and operates the rod 22 in the manner of an engine connecting rod. Said rod moves up and down in the swivel eye 23, which itself turns on the swivel axis, and the end of the pointer moves through an oval path, indicated by the dotted line 31. About half of said path is outside and the other half inside of the housing enclosing the upper end of the rod.

Thus when a washing, drying or other treating operation has been concluded, the operator, without opening the tub door, can stop the machine and then inch the cylinder in one direction or the other while observing the pointer 22a. When he sees that pointer emerge from the slot and move either up or down to a position opposite the indicating mark, he knows that the cylinder door has been properly registered with the tub or casing door, enabling him to stop the machine in that position and open both doors for inserting or removing work. Thus, all danger is avoided incident to inching the cylinder while the tub door is opened.

Of course, in applying the invention to a compartment washer in which the drum is equipped with radial or diametrical partitions dividing the space within it into compartments, requiring two, three or more doors spaced circumferentially of the cylinder, the indicating means described will be used in multiple as many times as there are doors distributed around the cylinder. In other words, with a diametrical partition forming two compartments, with two doors spaced 180°, two sets of indicating devices may be employed, located side by side, with their crank arms disposed at 180° to each other or on opposite sides of the central axis. This will require crank arms of the form employed on multiple cylinder internal combustion engines, but no other change, and will provide a separate indicator for each door, enabling either one or the other to be registered with the tub door, as will be readily understood by those skilled in the art.

Other advantages of the invention will be apparent without further description.

What I claim is:

1. A device for indicating the angular position of the rotatable door closed drum of a washing

machine including a door closed casing enclosing the drum and a shaft supporting the drum and extending to the outside of the casing, said device comprising a crank adapted for attachment to one end of the shaft, a rod pivotally connected at one end to said crank, and means for supporting said rod intermediate its ends for both sliding and pivoting motion, whereby the other free end of the rod travels in an endless elliptical path and by its position in said path indicates the position of the drum door relative to the casing door.

2. A device for indicating the angular position of the rotatable door closed drum of a washing machine including a door closed casing enclosing the drum and a shaft supporting the drum and extending to the outside of the casing, said device comprising a crank adapted for attachment to one end of the shaft, a rod pivotally connected at one end to said crank, means for supporting said rod intermediate its ends for both sliding and pivoting motion, and a housing enclosing the upper free end of the rod and having a vertical slot, the free end of the rod being provided with a pointer extending through said slot and arranged to travel in an endless elliptical path partly within and partly outside of said housing and by its position in said path indicating the position of the drum door relative to the casing door.

3. A device for indicating the angular position of the rotatable door closed drum of a washing machine including a door closed casing enclosing the drum and a shaft supporting the drum and extending to the outside of the casing, said device comprising a crank adapted for attachment to one end of the shaft, a rod pivotally connected at one end to said crank, means for supporting said rod intermediate its ends for both sliding and pivoting motion, and a housing enclosing the upper free end of the rod and having a vertical slot and an indicating mark at one side of said slot, the free end of said rod being provided with a pointer which travels back and forth along said slot and the end of which moves in an endless elliptical path partly within and partly outside of said housing and by its position with reference to said mark indicates the position of the drum door relative to the casing door.

4. Apparatus of the character described in claim 3, including means whereby said rod pointer and indicating means may be adjusted relatively to each other.
